RAIL ANCHOR

Filed June 25, 1930

FIG. 2

FIG. 3

INVENTOR.
John A. Bodkin.
BY Maurice Block
ATTORNEY.

UNITED STATES PATENT OFFICE

JOHN A. BODKIN, OF NEW YORK, N. Y.

RAIL ANCHOR

Application filed June 25, 1930. Serial No. 463,598.

This invention relates to anticreepers or rail anchors, and has for one of its objects the provision of a device of this character that will be positive in action.

Another object of the invention is to produce a rail anchor which may be termed universal; that is a single size of the said anchor will accommodate any size rail.

A further object of the invention is to provide a rail anchor that will automatically tighten its grip upon a rail due to any creeping action thereof.

A still further object of the invention is to provide a rail anchor, comprising a lever 15 adapted to engage one side of a rail base and passing thereunder alongside a railroad tie to the opposite side thereof, where the said lever is provided with a threaded portion having a nut threaded thereon and in engagement with the web of the rail, so that any creeping tendency of the rail will cause the lever to partly rotate in the nut to further tighten the rail.

A yet further object of the invention is 25 to provide a rail anchor of this character, that is so formed, that when the nut is fully tightened, the forward edge of a flat side thereof will engage the upper or fillet surface of the rail base to prevent any rotary movement of the said nut, and to cause the lever to be partly rotated by the tie, due to any creeping action of the rail.

Another object is to produce a device of the character described in which the maximum simplicity of construction and operation is secured.

Other objects and advantages will appear as the nature of the improvements is better understood, the invention consisting substantially in the novel arrangement and correlation of parts herein fully described, and illustrated in the accompanying drawings, wherein similar reference characters are used to describe corresponding parts throughout the several views, and then finally pointed out and specifically defined and indicated in the appended claims.

The disclosure made the basis of exemplifying the present inventive concept suggests a practical embodiment thereof, but the in-

vention is not to be restricted to the exact details of this disclosure, and the latter, therefore, is to be understood from an illustrative, rather than a restrictive standpoint.

The inventive idea involved is capable of 55 receiving a variety of mechanical expressions, one of which, for the purpose of illustration, is shown in the accompanying drawings, in which

Figure 1 is a fragmental perspective view 60 partly in section of a railroad track embodying a preferred form of my invention.

Figure 2 is an end section of a rail with my improved anchor applied thereto and

Figure 3 is a side view thereof looking 65 from the right of Figure 2.

Referring to the drawings in detail 5-5 indicate a pair of track rails suitably supported upon ties 6 one of which is shown in the drawings.

In engagement with the left side of the rail base 7 is a hook portion 8 of a lever 9, the bottom 10 of which passes underneath the rail base 7 adjacent the tie 6 and then extends upwardly as at 11 and terminates in a downwardly sloping threaded portion 12, upon which there is threadedly mounted a nut 13 in abutment with the web portion 14 of the rail 5.

Both the lever and the nut are provided 80 with a right hand thread and the nut is of such thickness that it will extend beyond the rail head 16, to permit the nut to be tightened against the web by means of a track wrench. The abutting surface of the nut is 85 chamfered so that the fillet 17 will not interfere with the tightening of the nut. However, when fully tightened, the forward edge 18 of one of the flat faces of the nut will engage the upper surface of the base 7 to prevent any further rotation of the nut.

To properly apply the device, the trackman stands in the track facing in the direction of creep indicated in Figures 1 and 3 95 by an arrow 20, the direction of creep being the same as the direction of traffic, and applies the nut side of the anchor to the right side of the rail web, and the portion 10 against the tie 6. The nut 13 is then tight- 100

ened against the web 14 by unwinding same from the extension 12.

From the foregoing, it will be seen that when there is any tendency for the track to creep, the device being tight on the rail, the stationary tie 6 will cause the lever 9 to partly rotate in the nut 13 as shown in dot and dash lines Fig. 3 to further tighten the rail against the tie and hold the said rail from creeping.

It will also be seen that owing to the slope of the portion 10 of the lever 9, and the distance between the hook portion 8 and the vertical portion 11, the said lever is adapted to be used in connection with any size rail base, whether in width or thickness.

It will further be seen that I have provided an anti-creep device, that when once secured to a track rail, cannot accidentally become loose and lost.

Having described my invention, what I claim as new and desire to secure by Letters Patent is:

1. In combination, a stationary part of a road bed, a rail having a base and web, an anti-creep lever in engagement with one edge of the base and the stationary part of the road bed, and a nut threadedly maintained on the said lever adapted to engage the rail at the juncture of the web and the opposite side of the base.
2. A rail anchor, comprising a hook, a portion sloping downwardly therefrom, a second hook portion at the opposite end of the lower portion, terminating in a threaded section sloping downwardly and inwardly, and a nut on the said section for the purpose specified.

JOHN A. BODKIN.
